PNEUMATIC TUBE CABINET

Edward J. Voitas, Oakland, N.J., assignor to International Telephone and Telegraph Corporation, Nutley, N.J., a corporation of Maryland

Filed June 21, 1963, Ser. No. 75,458

Term of patent 14 years

(Cl. D62—1)

Fig. 1

Fig. 2

Fig. 3

Fig. 4

Fig. 5

Fig. 6

Fig. 7

FIGURE 1 is a front view of a pneumatic tube cabinet, showing my new design;

FIGURE 2 is a top plan view thereof;

FIGURE 3 is a rear elevation thereof;

FIGURES 4 and 5 are side views of the cabinet of FIGURE 1; and

FIGURES 6 and 7 are respectively front and rear perspective views thereof.

The characteristic feature of my design resides in the front of the pneumatic tube cabinet housing as shown in FIG. 1.

I claim:

The ornamental design for a pneumatic tube cabinet, as shown and described.
